UNITED STATES PATENT OFFICE.

JACOB BUCHLI, OF BADEN, SWITZERLAND.

COMBINED STEAM AND INTERNAL-COMBUSTION LOCOMOTIVE.

Application filed November 5, 1923. Serial No. 672,753.

To all whom it may concern:

Be it known that I, JACOB BUCHLI, a citizen of Switzerland, residing at Baden, Switzerland, Felsemstrasse 2, have invented certain new and useful Improvements in or Relating to Combined Steam and Internal-Combustion Locomotives, of which the following is a specification.

This invention relates to combined steam and internal combustion locomotives and has for its object to provide a locomotive which is not open to the disadvantages of those previously proposed.

Hitherto difficulty has been experienced in finding the necessary space for the internal combustion engines without rendering the working parts of the apparatus inaccessible or on the other hand to prevent difficulties arising during the working of the locomotive such for example as obscuring the driver's view of the track.

According to this invention the internal combustion engines are so arranged adjacent to the steam generator that the axes of their cylinders are approximately at right angles to the longitudinal axis of the vehicle, the crank shafts driven by the internal combustion engines being disposed parallel to the longitudinal axis of the vehicle and geared through toothed wheels to the axles which are also driven by the steam engine.

Preferably the internal combustion engines are arranged on either side of the generator with the axes of their cylinders approximately vertical, the cylinders being of such height as not to interfere with the view of the track from the driver's cab.

One construction of the locomotive according to this invention is illustrated by way of example in the accompanying drawings, in which—

Figure 1 is a side elevation.

Figure 2 is a plan, and

Figure 3 a sectional end elevation.

In the construction shown the steam generator *a* of the locomotive has disposed on either side of it the groups of cylinders *b* of the internal combustion engines, the internal combustion engine being so arranged that the axes of their cylinders are at right angles to the longitudinal axis of the ve-

hicle and approximately vertical. The internal combustion engines drive crank shafts *c* which are parallel to the longitudinal axis of the vehicle and these crank shafts drive through two bevel pinions *d d'* a countershaft *e* which in turn drives a crank shaft *g* through pinions *f f'* the crank shaft *g* being coupled by rods *h* to the driving wheels *i*.

With such an arrangement great power can be obtained from a large number of relatively small cylinders and these cylinders can be so dimensioned and arranged that the driver's view of the track from the cab is not obstructed. At the same time the torque acting on the crank shaft is rendered uniform owing to the relatively large number of internal combustion engine cylinders.

I claim:

1. In a combined steam and internal combustion locomotive the combination of the internal combustion engines so disposed adjacent to the steam generator that the axes of their cylinders are approximately at right angles to the longitudinal axis of the locomotive with crank shafts arranged parallel to the longitudinal axis of the locomotive and geared through pinions to the axles also driven by the steam engines.

2. In a combined steam and internal combustion locomotive the combination of the internal combustion engines so disposed adjacent to the steam generator that the axes of their cylinders are approximately at right angles to the longitudinal axis of the locomotive, with crank shafts arranged parallel to the longitudinal axis of the locomotive and geared through pinions to the axles also driven by the steam engines, the cylinders of the internal combustion engine being so arranged on either side of the generator that their axes are approximately vertical, the cylinders being of such height as not to interfere with the view of the track from the driver's cab.

In testimony whereof I have affixed my signature in presence of two witnesses.

JACOB BUCHLI.
